YARN WINDING MACHINERY

William Harry Kimpton, Spordon, near Derby,
England, assignor to Celanese Corporation of
America, a corporation of Delaware

Application October 3, 1939, Serial No. 297,653
In Great Britain October 11, 1938

10 Claims. (Cl. 242—45)

This invention relates to yarn-winding machinery, and is particularly concerned with a yarn-winding device of the type in which the collecting package is rotated by a slipping frictional drive so as to collect the yarn as fast as it is delivered to the device.

In winding devices of this kind the tension under which the yarn is wound depends upon the radius of the package at which the yarn is wound and upon the frictional torque applied to the package to cause it to rotate. Since the radius at which the yarn is wound varies from the inside to the outside of the package the tension in the yarn during winding is apt to vary also. While the variations may be in part compensated by allowing the weight of the package to give rise to the frictional torque driving the package and so to cause said torque to increase as the weight of the package increases, this compensation may be inadequate or excessive and in any case makes it difficult to control even the average value of the tension under which the yarn is wound. It is an object of the present invention to provide a winding device in which the winding tension of the yarn may be adjusted and may, moreover, be made substantially constant throughout the winding operation.

According to the present invention a yarn-winding device comprises two friction elements adapted to provide a slipping frictional drive for a yarn package, a support adapted to carry a component part of the weight of the yarn package while the remaining component only of said weight acts to press said friction elements together to provide the necessary driving torque. The arrangement is preferably such that not only is a part of the weight of the package relieved so that it does not press the friction elements together but also, as the package increases in weight, a like part of the additional weight is also relieved, so that the component part that is relieved and the remaining component are both in linear relation to the total weight of the package throughout the winding operation. That is to say, every increment in the weight of the package produces an exactly proportional (but smaller) increment, both in the pressure between the friction elements and in the part of the weight relieved.

The carrying of part of the weight of the package otherwise than on the friction and driving means may be effected by any convenient means. Thus, for example, the package may be hung in arms swinging about a horizontal axis or pivot, the centre of gravity of the package and arms be-

ing deflected from beneath said pivot by contact of one of the friction elements with the other, the latter being attached to the package. In this way a component part of the weight of the package presses the friction elements together, while the remaining component of the weight of the package is carried by the arms. The relative magnitudes of the two components depend on the shape of the triangle of forces formed by the vertical through the centre of gravity of the package, a line joining the centre of gravity of the package to the axis about which it is swung, and the line normal to the contact between the friction elements, i. e. through the contact and at right-angles to the contacting surfaces.

Another method by which part of the weight of the package may be carried involves the use of two springs or spring systems, one of which reacts against a stationary part of the machine while the other produces a reaction between two friction elements by pressing them together. By this means, as the weight of the package increases both springs or spring systems are deflected by the same amount, the sum of the forces producing the deflections of the two springs being equal to the additional weight of the package while only the force producing the deflection of one spring increases the pressure between the friction elements and consequently the torque driving the package.

The device of the present invention is particularly convenient in the collection of large numbers of yarns after they have been submitted simultaneously to a liquid treatment or to some other treatment. For this purpose a large number of devices in accordance with the present invention may be mounted in the form of a creel for the simultaneous collection of the yarns. The invention is particularly convenient in this connection as it enables the taking up of a slack length of yarn produced during the changing of a yarn package. This is made very easily possible by reason of the fact that the invention enables the degree of slip occurring in the slipping frictional drive to be greatly increased without detriment to the tension conditions under which the yarns are collected. Thereby the package is enabled to rotate at a speed very much higher than its normal speed for the purpose of taking up a slack length.

Further, provision may be made for the collection of yarn delivered during a package changing operation by the provision of a waste drum secured to one of the frictional driving elements, i. e. the element to which the package itself is

normally secured for driving purposes. To enable the yarn to be collected on such a drum during the changing of a package, a stationary guide, into which the yarn is slipped when the package is to be changed, may be provided in the neighbourhood of the drum. Alternatively the ordinary traversing guide employed in the building of the package may be adapted to take up a stationary position opposite the waste drum when required to do so.

Two forms of apparatus according to the invention will now be described in greater detail with reference to the accompanying drawings, in which—

Fig. 1 is a front elevation of one form of device according to the invention; 15

Fig. 2 is a side elevation of the device shown in Fig. 1;

Fig. 3 is a detail of the same device; and 20

Fig. 4 is a cross-sectional view of another form of device according to the invention.

Referring to Figs. 1-3, the device shown therein comprises a spindle 1 on which is mounted a package 2 for receiving the yarn, which is led to the package and traversed to and fro along its length by means of a traversing guide 3 mounted on a reciprocating guide bar 4. The spindle 1 has reduced ends 5 each of which drops into a slot 6 in a piece 7 spigoted into an arm 8 and secured therein by means of a screw 9. The two arms 8 are pivoted at their upper ends to a rod 10 which is secured in two bearings 11 by means of set screws 12. Nuts 13 at each end of the rod 10 retain the arms on the ends of the rod without preventing them from pivoting relatively to the rod. The bearings 11 are formed at the ends of rods 14 inserted in bores 15 in a bracket 16 and slideable in and out of said bores. The rods 14 are secured in the bores 15 by means of locking screws 17. The bracket 16 is itself mounted on a bar 18, forming part of the frame of the machine, the bar 18 fitting into a slot 19 in the bracket, while a set screw 20 is provided to secure the bracket 16 at any desired height. By means of the set screws 17 and 20, the horizontal and vertical position of the rod 10 on which the arms 8 are pivoted may be adjusted as desired.

The spindle 1 on which the package 2 is mounted carries a friction wheel 21 constituting one of the friction elements for the purposes of the invention, the other friction element being in the form of a friction wheel 22 mounted on a driving shaft 23.

Pressure between the two driving elements 21, 22 is provided primarily by the weight of the package 2 and the arms 8, and the inclination to the vertical of a line joining the rod 10 and the spindle 1, the engagement of the friction wheel 22 with the friction wheel 21 deflecting this line from the vertical. In order that the initial pressure between the friction elements 21, 22 may be adjusted, there is provided a spring 24 attached at one end to an arm 25 attached by means of a set screw 26 to a rod 27 joining the middles of the two arms 8. The other end of the spring 24 is secured to a screw 28 which passes through a small bracket 29 in the middle of the rod 10 and is engaged by a screw 30 bearing upon the bracket 29. The bracket 29 is secured to the rod 10 by means of a set screw 31. By rotation of the screw 30 the spring 24 may be brought to any desired state of tension and the initial pressure between the friction elements 21, 22 may thus be adjusted.

In the operation of the device the position of

the rod 10 is adjusted by means of the set screws 17, 20 and by moving the rod 14 and bracket 16 until the desired proportion of the weight of the package is pressing the friction elements 21, 22 together, and the screw 30 is then adjusted in order to give the desired initial pressure between the elements 21, 22 so as to bring about the desired tension in the yarn at the beginning of the winding operation. The position of the rod 10 being properly adjusted, this tension in the yarn is maintained with small variation through the winding operation, the additional driving torque required to produce the desired tension when the radius of yarn on the package increases being brought about by an increase of the pressure between the friction elements 21, 22 arising from the increased weight of yarn on the package.

The device shown in Fig. 4 comprises a vertical spindle 35 carried in a footstep bearing 36 and capable of rotating freely therein, the footstep bearing 36 being mounted in the frame 34 of the machine. The hardened pad 37 of the bearing 36, which takes the weight of the spindle 35, is carried on screw means comprising a vertical screw 38 with a lock nut 39 so that its height may be adjusted as desired. The upper end 40 of the spindle 35 is hollow in order to receive a spring system comprising short piston-like member 41 disposed between two springs 42, 43, the lower spring 42 bearing against the bottom of the hollow portion 40 being stiff and the upper spring 43 being relatively light. The upper end of the hollow portion 40 of the spindle 35 is closed with a plug 44 secured therein, through which passes a screw 45, with a lock nut 46 outside the plug, the end of the screw 45 inside the plug 44 bearing against a pad 47 above the light spring 43. Two vertical slots 48 are provided in the hollow part 40 of the spindle at diametrically opposite points, and through said slots protrude pins or screws 49 extending from the piston 41 contained within the spindle 35. The spindle 35 is surrounded by a sleeve 50 into which said pins or screws 49 project, and the lower end of the sleeve 50 carries a platform 51 on which a bobbin 52, slipped over the sleeve 50, may rest, the sleeve 50 and platform 51 together constituting a support for the yarn package 52. It will be seen that the springs 42, 43 are each connected at one end to the support 50, 51 through the members 41 and pins 49, and at the other end to the frame 34 respectively through the screw means 38, 39 and through the screw means 45, 46, 47. The pins 49, by extending through the vertical slots 48 into the sleeve 50, cause the spindle 35, sleeve 50 and platform 51 to rotate together as a unit, but permit a limited degree of vertical motion of the sleeve 50 and platform 51 relatively to the spindle 35.

Surrounding the solid lower part 53 of the spindle 35 and mounted thereon by means of ball bearings 54 is a driving whorl 55 adapted to be driven by engagement with a belt or other suitable member. The driving whorl 55 is provided with a flat upper face 57 against which bears a friction pad 58 secured to the underside of the platform 51 carrying the bobbin 52. The pressure between the contacting friction elements 57, 58 is derived from the support 50, 51 and is communicated by a spring system consisting, in the embodiment here described, of a single leaf spring 59. Surrounding the upper part of the whorl 55, and capable of rotating with respect thereto, is a drum 60 serving as a waste drum, which is provided with a flange 61 at its lower

edge, and is overlapped at its upper edge by a skirt 62 depending from the platform 51 which carries the bobbin 52. The waste drum 60 is capable of rotating with the whorl 55, and tends to do so on account of a packing of thick lubricant, such as a mixture of vaseline and graphite in grooves 63 inside the drum. The drum, however, may be stopped, or may be permitted to rotate at any angular speed lower than that of the whorl 55. A traverse guide 64 is provided in the form of a wire pigtail projecting from a block 65 that slides in a vertical guide in the form of a slotted tube 66, being suspended by means of a light spring 67 (for which a cord and counter-weight may be substituted), and actuated from below by a cord 68 or like flexible member, to traverse up and down the length of the bobbin. When the waste drum 60 is being used the block 65 may be driven down to its level and locked by rotating it so that the pigtail 64 lodges under the recess indicated at 69, so that it remains stationary opposite the drum till it is required to traverse again. A vertical slot 70 is provided on the drum 60 to facilitate the removal of waste.

In the operation of the device the weight of the bobbin 52 and of the platform 51 and the tube 50 surrounding the spindle 35 are carried in part by the stiff spring 42 within the spindle 35, the weight being transmitted through the pins or screws 49 extending into the walls of the tube 50, and through the piston member 41 into which the pins or screws 49 are fitted. The slots 48 in the hollow part of the spindle 35 allow the weight to be freely carried by the lower spring 42 in this manner. This part of the weight is therefore carried ultimately by the footstep bearing 36 at the bottom of the spindle. Part of the weight of the bobbin 52 and of the tube 50 and platform 51, however, are transmitted through the leaf spring 59 and friction pad 58 to the flat upper surface 57 of the driving whorl 55. As the weight of the bobbin 52 increases both the leaf spring 59 and the springs 42 and 43 within the hollow spindle 35 are deflected so that, although the pressure between the friction pad 58 and the upper surface 57 of the whorl 55 is increased, it is not increased by the full amount by which the weight of the package 52 is increased.

In adjusting the device, an empty bobbin may be placed on the platform 51, and the height of the footstep bearing 37 may then be adjusted until there is no driving contact between the friction pad 58 and the upper surface 57 of the driving whorl. It will be understood that the raising of the footstep bearing 37 lifts the whole of the spindle 35, tube 50, platform 51, and bobbin 52 independently of the driving whorl 55. The screw means 38, 39, used in this way, act as a coarse adjustment for the pressure between the friction pad 58 and the surface 57. When the driving pressure has been entirely released the screw 45 in the plug 44 at the top of the spindle 35 may then be screwed down until the desired pressure between the friction pad 58 and the upper surface 57 of the whorl 55 is obtained. This may conveniently be determined by placing a half-full bobbin on the platform 51, and applying the desired tension to the end of the yarn thereon; the screw 45 is adjusted until the bobbin rotates independently of the whorl 55 by slipping of the friction pad 58. Since the screw 45 bears on the top of the light spring 48 inside the hollow spindle 35 a substantial movement of the screw 45 is required to bring about the desired pressure and fine adjustment of the pressure and

consequently the tension ultimately produced in the yarn may be obtained.

Having described my invention, what I desire to secure by Letters Patent is:

- 5 1. A yarn winding device comprising two contacting friction elements adapted to provide a slipping frictional drive for a yarn package, a support for said yarn package secured to one of said frictional elements, said support being adapted to carry the total weight of said package and the parts of the device associated therewith, and to communicate, as a pressure between said friction elements, a component of said total weight that is in linear relation thereto throughout the winding operation, and means for relieving said friction elements of the remaining component of said total weight, which is likewise in linear relation thereto, whereby the pressure between said friction elements enables them to provide for the yarn package the desired driving torque increasing with the increasing diameter of the package.
- 10 2. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 15 3. A yarn winding device comprising an adjustable pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, and is adjustable by adjusting the position of said pivot, said friction wheels being relieved of the remaining component by said pivot, and means for driving said second friction wheel to provide for said package a slipping frictional drive of the desired torque increasing with the diameter of the package.
- 20 4. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, an adjustable spring secured to said support to adjust the initial pressure between said friction wheels, and means for driving said second friction wheel to provide for said package a slipping frictional drive of the desired torque increasing with the diameter of the package.
- 25 5. A yarn winding device comprising an adjustable pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 30 6. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 35 7. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 40 8. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 45 9. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 50 10. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 55 11. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 60 12. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 65 13. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 70 14. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.
- 75 15. A yarn winding device comprising a pivot, a support swinging below said pivot and adapted to carry the weight of a yarn package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation, said friction wheels being relieved of the remaining component by said pivot, and means for driving said second friction wheel to provide for said package a slipping frictional drive of the desired torque increasing with the diameter of the package.

package, a pair of friction wheels, one adapted to be secured to said package, and the second contacting with the first and displacing said support from beneath said pivot, whereby there is communicated, as a pressure between said friction wheels, a component of said weight that is in linear relation thereto throughout the winding operation and is adjustable by adjusting the position of said pivot, said friction wheels being relieved of the remaining component by said pivot, an adjustable spring secured to said support to adjust the initial pressure between said friction wheels, and means for driving said second friction wheel to provide for said package a slipping frictional drive of the desired torque increasing with the diameter of the package.

6. A yarn winding device comprising a frame, two contacting friction elements adapted to provide a slipping frictional drive to a yarn package, a support for said yarn package, a spring system between said support and one of said friction elements adapted to communicate, as a pressure between said friction elements, a component of the total weight of said package and support that is in linear relation to said total weight, and a second spring system between said support and said frame adapted to relieve said friction elements of the remaining component of said total weight, whereby the pressure between said friction elements enables them to provide for the yarn package the desired driving torque increasing with the increasing diameter of the package.

7. A yarn winding device comprising a frame, two contacting friction elements adapted to provide a slipping frictional drive to a yarn package, a support for said yarn package, a spring system between said support and one of said friction elements adapted to communicate, as a pressure between said friction elements, a component of the total weight of said package and support that is in linear relation to said total weight, a light spring and a heavy spring each connected at one end to said support and at the other to said frame and adapted to act as a second spring system to relieve said friction elements of the remaining component of said total weight, whereby the pressure between said friction elements enables them to provide for the yarn package the desired driving torque increasing with the increasing diameter of the package, and screw means between each of said springs and said frame providing a fine and a coarse adjustment respectively for the initial pressure between said friction elements.

8. A yarn winding device comprising two contacting friction elements, one driving and one driven, adapted to provide a slipping frictional drive for a yarn package, a support for said yarn package adapted to carry the total weight of said package and the parts of the device associated therewith, and to communicate, as a pressure be-

tween said friction elements, a component of said total weight that is in linear relation thereto throughout the winding operation, means for relieving said friction elements of the remaining component of said total weight, which is likewise in linear relation thereto, whereby the pressure between said friction elements enables them to provide for the yarn package the desired driving torque increasing with the increasing diameter of the package, and a waste drum frictionally connected to said driving element, so as to be capable of being rotated thereby or to be readily prevented from rotating.

9. A yarn winding device comprising a frame, two contacting friction elements, one driving and one driven, adapted to provide a slipping frictional drive to a yarn package, a support for said yarn package, a spring system between said support and the driven friction element adapted to communicate, as a pressure between said friction elements, a component of the total weight of said package and support that is in linear relation to said total weight, a second spring system between said support and said frame adapted to relieve said friction elements of the remaining component of said total weight, whereby the pressure between said friction elements enables them to provide for the yarn package the desired driving torque increasing with the increasing diameter of the package, and a waste drum frictionally connected to said driving element, so as to be capable of being rotated thereby or to be readily prevented from rotating.

10. A yarn winding device comprising a frame, two contacting friction elements, one driving and one driven, adapted to provide a slipping frictional drive to a yarn package, a support for said yarn package, a spring system between said support and the driven friction element adapted to communicate, as a pressure between said friction elements, a component of the total weight of said package and support that is in linear relation to said total weight, a light spring and a heavy spring each connected at one end to said support and at the other to said frame and adapted to act as a second spring system to relieve said friction elements of the remaining component of said total weight, whereby the pressure between said friction elements enables them to provide for the yarn package the desired driving torque increasing with the increasing diameter of the package, screw means between each of said springs and said frame providing a fine and a coarse adjustment respectively for the initial pressure between said friction elements, and a waste drum frictionally connected to said driving element, so as to be capable of being rotated thereby or to be readily prevented from rotating.
